DANIEL M. LE FEVER, OF SYRACUSE, NEW YORK, ASSIGNOR TO PASS & SEYMOUR, INCORPORATED, OF SYRACUSE, NEW YORK, A CORPORATION OF NEW YORK

LAMP-SOCKET DEVICE

Application filed February 11, 1926. Serial No. 87,646.

This invention relates to lamp socket devices and more particularly to locking means for preventing the unscrewing of sockets which are attached to fixtures by having their outer shells threaded into apertures in the fixtures.

It is a general object of the present invention to provide a novel and improved device for securing lamp sockets in fixtures and preventing their unscrewing under any conditions.

More particularly it is an object of this invention to provide a one-way locking or securing device for preventing sockets from becoming unscrewed from fixtures in which they are mounted.

In general the invention may be said to comprise a locking slide adapted to be arranged in a recess in one of the threads of a pair of complementary threaded members, said slide being provided with means to cause it to move to a position to wedge between the two threads upon an attempted unscrewing of the two members.

The invention may be best understood by reference to the following specification and the accompanying drawings wherein is disclosed, by way of example, only, a single embodiment of the present invention, with the understanding, however, that various changes may be made therein by those skilled in the art without departing from the spirit of the invention or the scope of the appended claims.

In said drawings:

Fig. 1 is a section through a fixture of a well known type showing a pair of sockets constructed according to the present invention mounted therein;

Fig. 2 is a side elevation of a socket;

Fig. 3 is a transverse section on line 3—3 of Fig. 2 showing the slide in its unlocked position;

Fig. 4 is a similar view showing the slide in its maximum locked position; and

Fig. 5 is a partial vertical section on line 5—5 of Fig. 2.

The last four figures are shown larger than natural size.

In the electric lighting art there are at present used a number of styles of fixtures

which may be generically termed "pan type". In general their form is somewhat that of a tin washbowl placed with its open side against the ceiling and with lights projecting normally from the surface thereof. These fixtures are of course made up in artistic style to harmonize with the surrounding furnishings. In the earlier development of these fixtures they were made of thin sheet metal and provided with circular holes punched in the metal to receive sign type receptacles which are of the two-part porcelain construction. The screw shell of the socket passed through the hole, and a porcelain ring was threaded on the same to hold the socket in place. This construction was objectionable from the artistic standpoint for the porcelain rings were visible. The better manufacturers endeavored to avoid this by using the conventional form of brass shell receptacle provided near its end with a thread to receive a shade ring. This thread was engaged with a complementary thread formed in a pressed-in sleeve in the pan, the bead on the socket forming a stop to prevent the socket from extending through the hole and projecting into view on the outside of the fixture. This form of construction, while excellent from the artistic standpoint, was nevertheless subject to objections. The socket being screwed into position from the inside was loosened when lamps were screwed into the socket, for the movement tending to tighten the lamp in the socket likewise tended to loosen the socket in the fixture. It hence became necessary to solder the shell of the socket to the pan on the inside.

Another and later development of the pan type fixture required it to be more irregular in shape with designs in relief on the outer surface thereof and such fixtures are molded of soft metal in a slush mold. The metal is so soft that it is not readily soldered, so that other means had to be resorted to to retain the sockets in position. Sometimes wax or other compound was poured around the socket on the inside of the fixture so as to hold the socket in position, but this is at best a make-shift and an expensive and messy job.

The present invention contemplates the provision of a locking means on the socket adapted to cooperate with the material of the threads in the hole in the fixture, no matter what its composition, which, while allowing the socket to be readily threaded into the fixture, prevents it from being backed out or unscrewed.

Referring to the drawing, there is disclosed in Fig. 1 at 10 a pan-type fixture of conventional form provided with any number, here shown as two, threaded openings 11 of a size to receive the shell of a socket. The socket of the present invention is disclosed generally at 12. The electrical features of the socket and the construction of the lamp retaining parts form no part of the present invention and have neither been shown nor will they be described. The exterior shell 13 of the socket is formed of a relatively soft metal which can be pressed or drawn into the form of a cup having a closed bottom 14, straight cylindrical sides and an open end 15 to receive the lamp base. Near the open end there is pressed or otherwise formed an external circumferential bead 16, which is adapted to fit against the inner surface of the fixture to form a limiting stop as shown in Fig. 1. Just beyond the bead the metal is pressed into screw threads 17 best shown in Fig. 2 adapted to be threaded into the complementary threads in the opening 11 in the fixture so that the socket can be threaded into the opening from the inside of the fixture and project but slightly from the outside of the fixture.

To prevent the socket from becoming unscrewed when a lamp such as 18 is screwed into the socket, a locking slide 19 is provided. This slide comprises a short arcuate section of thin resilient metal slightly narrower than the length of the threaded portion on the socket. To accommodate this locking slide 19 the threads 17 are stamped or pressed flat and inwardly of the general surface of the shell 13 to form the two spaced recesses 20 and 21 each having a width such as to allow free movement of the locking slide therein. A portion of the thread between these two recesses is retained intact as shown at 22. The recess 21 has its bottom wall concentric with the wall 13 of the socket and cut away from the same at its ends between apertures 23 and 24. The aperture 23 also separates this wall from the retained portion of the threads 22. In a similar manner the aperture 25 separates the other recess from the portion 22. The outer surface of the bottom wall 26 of the recess 21 is a sufficient distance below the inner surface of the portion 22 to accommodate the thickness of the locking slide 19 which is threaded through the apertures 23 and 25 so as to lie with its ends in the recesses 20 and 21 and its intermediate section beneath the part 22. The

slide is sufficiently resilient to allow it to be sprung into this position after which the part 22 prevents it from being displaced.

The bottom wall 27 of the recess 20, is, adjacent the aperture 25, depressed to the same depth as the wall 26 of the other recess, but from that point gradually slopes outwardly to the tops of the threads 17 as best shown in Figs. 3 and 4.

The locking slide is of a length somewhat less than the aggregate length of the two recesses and the portion 22 and its ends are turned upward substantially normal to its arcuate intermediate portion. These upturned ends are, however, not of sufficient length to reach quite to the curved surface forming the limit of the threads 17. The upturned end or lug 28 which lies in the recess having a sloped bottom is cut off square on its end, whereas the end 29 is clipped as shown at 30 in Fig. 5, so that its extreme tip lies in the extension of the thread against which it can abut when the slide is in the position shown in Fig. 3 with the upturned end against the edge of the aperture 24 which forms a limiting stop for the same.

The sharp tip 30 is, owing to the resilience of the slide 19, caused to lightly engage the threads in the opening 11 in the fixture when the socket is being screwed into position and at all times when it is in position. Assuming that the thread is a right hand one, then the slight engagement of this tip 30 with the threads in the opening 11 serves to retain the locking slide in the position shown in Fig. 3 with the tip 28 just above the lowest portion of the inclined bottom 27 so that it is not projected out into engagement with the tips of the threads in the opening 11. The slide remains in this position while the socket is being screwed into the aperture in the fixture.

Upon an attempted unscrewing of the socket, the locking slide, by virtue of the engagement of its tip 30 with the thread in the fixture, remains stationary, and the socket moves slightly in respect to it but in so doing the portion of the locking slide adjacent the tip 28 is caused to slide up on the inclined surface 27 and project the tip into engagement with the threads in the fixture opening. This further prevents any rotational movement of the locking slide so that any further attempt to unscrew the socket only serves to force the portion 28 harder against the threads of the opening in the fixture by virtue of the inclined bottom 27 sliding up on the locking lug, and thus the socket is effectively prevented from being unscrewed.

The portion 22 serves merely to retain the locking slide in position when the socket is not in the fixture and in consequence of this could be omitted. Therefore the two recesses adapted to receive the locking slide may be considered as a single large recess provided with a sloping or cam surface such as 27, at

one end thereof. The resilience of the locking slide allows it to be readily threaded into position by passing into the apertures 23 and 24 and the upturned ends 28 and 29 retain it 5 in position against any ordinary attempts to remove it by engaging the edges of the part 22, but at the same time the slide is loosely retained in position and can readily move to its proper place upon the occurrence of a reverse 10 movement of the socket shell.

The invention has been illustrated in conjunction with an electric socket and fixture, although it is obvious that it may be applied in a number of other cases where it is desired 15 to provide a non-removable threaded part.

Having thus described the invention, what is claimed as new and desired to be secured by Letters Patent is:

1. In a device of the class described, in 20 combination, a pair of complementary threaded members, one of said members having a portion of the threads removed to provide a recess, a bottom wall for said recess having one end sloping to the top of the 25 threads of its member in the direction of unscrewing said member, a locking slide loose in said recess, a portion thereof adapted to lightly engage the threads in said other member and a second portion thereon adapted to be 30 pressed into engagement with said other member by said sloping bottom wall upon an attempted unscrewing operation.

2. In a device of the class described, in 35 combination, a pair of complementary threaded members, one of said members having a portion of the threads removed to provide a recess, a bottom wall for said recess having one end sloping to the top of the 40 threads of its member in the direction of unscrewing said member, a locking slide loose in said recess, a portion thereof adapted to lightly engage the threads in said other member, a second portion thereon adapted to be 45 pressed into engagement with said other member by said sloping bottom wall upon an attempted unscrewing operation and means to retain said slide in said recess when the members are separated.

3. In an electric socket adapted to be 50 screwed into a threaded opening in a fixture, in combination, a shell having an external thread a portion of which is removed to form a recess having a bottom wall a portion of which slopes outwardly, a locking slide loosely 55 mounted in said recess, and means on said slide to draw the same away from said sloping bottom upon screwing said socket into said fixture.

4. In an electric socket adapted to be 60 screwed into a threaded opening in a fixture, in combination, a shell having an external thread a portion of which is removed to form a recess having a bottom wall a portion of which slopes outwardly, a locking slide loosely 65 mounted in said recess, and means on said

slide to draw the same up said sloping bottom upon an attempted unscrewing of said socket to lock the same in said fixture.

5. In an electric socket adapted to be 70 screwed into a threaded opening in a fixture, in combination, a shell having an external thread a portion of which is removed to form a recess having a bottom wall a portion of which slopes outwardly, a locking slide loosely 75 mounted in said recess, and means on said slide to engage the threads of said fixture to draw said slide away from said sloping bottom upon screwing said socket into said fixture.

6. In an electric socket adapted to be 80 screwed into a threaded opening in a fixture, in combination, a shell having an external thread a portion of which is removed to form a recess having a bottom wall a portion of which slopes outwardly, a locking slide loosely 85 mounted in said recess, and means on said slide to engage the threads of said fixture to draw said slide up said sloping bottom upon an attempted unscrewing of said socket to lock the same in said fixture.

7. In an electric socket adapted to be 90 screwed into a threaded opening in a fixture, in combination, a shell having an external thread a portion of which is removed to form a recess having a bottom wall a portion of which slopes outwardly, a locking slide loosely 95 mounted therein, means on said slide to engage the threads of said fixture to move said slide away from said sloping bottom upon screwing said socket into said fixture, and to cause said slide to move along and up said slope upon an attempted unscrewing of said socket to jam said slide between said socket and fixture to lock them together.

8. In an electric socket adapted to be 100 screwed into a threaded opening in a fixture, in combination, a thin shell having pressed threads to engage said fixture, two spaced 105 portions of said threads being flattened and pressed inwardly to provide recesses, said shell having apertures therethru at each end of one recess and at the end of said other recess adjacent the threaded section between 110 said recesses, a thin slide adapted to rest in both recesses and pass under the portion between them, said slide being shorter than the arcuate distance between remote ends of 115 said recesses, the unapertured end of one recess having its bottom wall sloping outwardly, and means on said slide to lightly engage the threads of said fixture when the socket is screwed into position.

9. In an electric socket adapted to be 120 screwed into a threaded opening in a fixture, in combination, a thin shell having pressed threads to engage said fixture, two spaced portions of said threads being flattened and pressed inwardly to provide recesses, said shell having apertures therethru at each end 125

- of one recess and at the end of said other recess adjacent the threaded section between said recesses, a thin slide adapted to rest in both recesses and pass under the portion between them, said slide being shorter than the arcuate distance between remote ends of said recesses, the unapertured end of one recess having its bottom wall sloping outwardly, and means projecting from said slide
- 10 to lightly engage the threads of said fixture when the socket is screwed into position, said means drawing the end of the slide away from said sloping bottom when the socket is being screwed in but causing said slide to
- 15 move up said slope to jam between it and the threads of the fixture upon attempted unscrewing of said socket.
10. In a device of the class described, in combination, a member having an internal thread, a second member having a complementary external thread, one of the said threads having a portion thereof omitted to form a recess and a cam surface leading from the bottom of said recess to the top of the corresponding threads, an elongated locking means in said recess and means to cause said locking means to slide along said cam surface upon an unscrewing operation to lock said threaded parts together.
- 30 10. In testimony whereof I hereunto affix my signature.

DANIEL M. LE FEVER.
